SCALP OILER

Filed Sept. 25, 1937

UNITED STATES PATENT OFFICE

2,123,558

SCALP OILER

Henry C. Altheide, Quincy, Ill.

Application September 25, 1937, Serial No. 165,762

2 Claims. (Cl. 132—13)

This invention is a device especially designed as a means for applying an oil, tonic, or shampoo liquid to the scalp and the hair; and in accordance with the invention the device is in the form 5 of a comb so as to convey the oil or tonic to the roots of the hair.

The invention together with its objects and advantages will be best understood from a study of the following description taken in connection 10 with the accompanying drawing wherein:

Figure 1 is a side elevational view of the device. Figure 2 is a sectional view taken substantially on the line 2—2 of Fig. 1 and

Figure 3 is an end elevational view of the device 15 on a reduced scale.

Referring to the drawing by reference numerals it will be seen that in the preferred embodiment thereof the device comprises an oil or fluid reservoir 5 which is preferably constructed of some 20 ductile material, preferably brass and is substantially rectangular in side elevational, and wedge shaped in end elevational, having the side walls 6—6 thereof gradually converging toward one end edge 7 of the reservoir.

25 At the end 7 of the reservoir the latter is open to conformably receive therein the head 8 of a comb member 9, the teeth 10 of which are integral with the head 8.

The comb member 9 consisting of the head 8 and teeth 10 is formed of hard rubber, "bakelite" or any other suitable and analogous material.

The teeth 10 are tapered as shown and are hollow, each being provided with a longitudinal duct 11 which communicates with the reservoir 5 35 through tapered opening 12 provided in the head 8 and in alignment with the teeth of the comb.

The reservoir 5 at one end thereof is provided with a filling neck 13 for which a cap 14 is provided.

40 It will be manifest that the reservoir 5 serves as a handle whereby to manipulate the comb as well as to contain the liquid, and to facilitate the expelling of the liquid or oil in the reservoir the walls 6 thereof are pressed inwardly, com- 45 pressing as it were, the reservoir.

The walls 6 are normally urged outwardly rela-

tive to one another through the medium of a spring device 15 which is formed from a rectangular sheet of metal or other suitable material bent into a substantial U to fit within the reservoir 5 as shown in Fig. 2 and at the closed end 5 of the U the spring 15 is riveted or otherwise secured to the end wall 16 of the reservoir as at 17.

From the above it will be seen that I have provided a device which is capable of being conveniently handled and thereby admirably serves as a medium for applying oil, tonic, or shampoo to the hair and scalp.

What is claimed is:—

1. A device for applying fluid to the scalp comprising a receptacle formed of spring metal and having an elongated substantially straight edge having an opening therein, a comb member including a head of elongated form and having tapered side edges and hollow teeth extending 20 from the small end of the head, said head having openings therein communicating with the teeth, said head fitting in the opening with the edge portions of the metal adjacent the opening bent over the tapered sides of the head. 25

2. A device for applying fluid to the scalp comprising a receptacle formed of spring metal and having an elongated substantially straight edge having an opening therein, a comb member including a head of elongated form and having 30 tapered side edges and hollow teeth extending from the small end of the head, said head having openings therein communicating with the teeth, said head fitting in the opening with the edge portions of the metal adjacent the opening bent over the tapered sides of the head, said head and the teeth being formed of hard non-metallic material and an elongated substantially U-shaped spring metal member located in the receptacle and having portions of its limbs engaging the 40 sides of the receptacle and means for attaching the bight part of said U-shaped member to that end of the receptacle opposite the edge having the opening therein.

HENRY C. ALTHEIDE. 45
